UNITED STATES PATENT OFFICE.

JACOB GOLDBERG, OF CINCINNATI, OHIO, ASSIGNOR TO THE GOLDBERG PADDING MACHINE COMPANY, OF CINCINNATI, OHIO, A CORPORATION OF OHIO.

UNIVERSAL FEED MECHANISM FOR SEWING MACHINES.

Application filed August 2, 1920. Serial No. 409,575.

To all whom it may concern:

Be it known that I, JACOB GOLDBERG, a citizen of the United States of America, and resident of Cincinnati, in the county of 5 Hamilton and State of Ohio, have invented a new and useful Improvement in Universal Feed Mechanism for Sewing Machines, of which the following is a specification.

My invention relates especially to sewing 10 machines having a feed shaft for the goods, such as are employed in blind stitch sewing machines, although it may be applied to machines of other types.

I will show and describe my device as applied to a blind-stitch sewing machine.

An object of my invention is to provide a feed mechanism whereby the feed may be so modified that the number of stitches per 20 inch may be readily and accurately varied and controlled.

Another object of my invention is to provide a feed mechanism in which the parts are so housed that they will offer no resistance to the material that is being fed, 25 and that the parts will not be obstructed in their operation by the material being fed thru such machine.

Another object is to provide a simple and efficient device for the purpose stated.

30 These and other objects are attained by the means described herein and disclosed in the accompanying drawing in which:

Fig. 1 is a fragmental side elevation of a blind stitch sewing machine to which a device embodying my invention has been applied.

Fig. 2 is a sectional view on line 2—2 of Fig. 1.

Fig. 3 is a fragmental sectional view on 40 line 3—3 of Fig. 1.

The housing A, containing within it a ratchet mechanism, is mounted on the feed shaft B, and is rotatably reciprocated by means of the rod C mounted upon the feed 45 arm D that is rotatably reciprocated by the rocker shaft E. The feed shaft B has mounted on it a series of feed rollers, not shown, that engage and feed the material to be sewed to the needle, not shown.

50 The housing A comprises a case a, a back a', and a cover a''. The feed shaft B extends thru the back a' and has mounted upon it, interiorly to the case a, a ratchet wheel b secured to shaft B by set screw b'.

55 The back a' is adapted to be rotatably re-

ciprocated upon the shaft B. A pawl a³ mounted upon the back a' interiorly to the case, normally engages the ratchet wheel b and is held in such engagement by the spring a⁴ mounted on the interior of the case. The 60 cover a² extends over one side of the case and encases the ratchet mechanism within such case. A lug a⁵ extends from the case and has pivotally mounted upon it one end of the rod C. The other end of the rod is ad- 65 justably mounted upon the feed arm D. The feed arm shaft d upon which the feed arm collar d' is mounted, is supported above the base F of the machine by means of the bracket f. The feed arm collar has a slotted 70 arm D along the slot d² of which the one end of the rod C may be moved, and at intermediate places of which the rod C may be secured by means of the screw d³ and the lock nut d⁴. A gear segment d⁵ is formed 75 on the collar d', said gear segment engaging gear segment e formed on the rocker shaft collar e' mounted on the rocker shaft e² supported on and above the shaft d by means of the links d⁶ and d⁷. The rocker arm E 80 operated by the eccentric G is mounted on the shaft e². The collar e' is secured upon the rocker shaft e² by means of set screw e³.

The operation of my device is as follows:

The eccentric G imparts an oscillatory and 85 rotary motion to the rocker shaft e² by means of the rocker arm E. This motion of the rocker shaft e² is transmitted to the collar e' the gear segment of which engages with the gear segment d⁵ formed on the feed arm collar thereby rotatably reciprocating the feed arm upon shaft d. The motion of the feed arm is transmitted to the lug a⁵, formed on the case a, by means of the rod C, whereby the pawl, operative upon the ratchet wheel b, intermittently revolves the feed shaft B. By adjusting the rod C to various distances along the feed arm from the center of the shaft d, the length of the stroke of the rod C is varied, whereby the number of 90 degrees thru which the shaft B is turned from one forward stroke of the rod C is varied. Adjustment of the rod C is made by loosening the thumb screw c³ and moving the rod C to the desired position upon the arm 100 D, whereupon the thumb screw is tightened.

What I claim is:

1. In a feed mechanism the combination with a feed shaft, of a rocker shaft and a feed arm shaft mounted adjacently to one 110

another, a rocker arm mounted on the rocker shaft and adapted to oscillate the rocker shaft, a collar mounted on the rocker shaft and having gear teeth formed thereon, a feed arm mounted on the feed arm shaft and having gear teeth formed thereon and engaging the gear teeth on the collar, a ratchet mechanism mounted on the feed shaft, and means to transmit the movement of the feed arm 10 to the ratchet mechanism.

2. In a feed mechanism the combination with a feed shaft, of a rocker shaft and a feed arm shaft mounted adjacently to one another, a rocker arm mounted on the rocker 15 shaft and adapted to oscillate the rocker shaft, a collar mounted on the rocker shaft and having gear teeth formed thereon, a feed arm mounted on the feed arm shaft and having gear teeth thereon engaging the teeth 20 on the collar, a ratchet wheel mounted on the feed shaft, a housing encasing the ratchet wheel, a pawl interiorly mounted on the housing and engaging the ratchet wheel, a

rod adjustably mounted at one end on the feed arm, and a pivot connecting the other 25 end of the rod to the housing.

3. In a feed mechanism the combination with a feed shaft, of a rocker shaft and a feed arm shaft mounted adjacent to one another, a rocker arm mounted on the rocker 30 shaft adapted to oscillate the rocker shaft, a gear segment mounted on the rocker shaft, a feed arm mounted on the feed arm shaft having gear teeth engaging the gear segment, the feed arm having an elongated slot 35 extending substantially radially to the axis of the feed arm shaft, a ratchet mechanism mounted on the feed shaft, a rod pivotally connected at one end with the ratchet mechanism, and having its other end extending 40 into the slot in the feed arm and adapted to be adjusted longitudinally thereof.

In witness whereof, I have hereunto subscribed my name this 30th day of July, 1920.

JACOB GOLDBERG.
